GRINDING MACHINE

Harold L. Blood, Birmingham, Mich., and Walter H. Pickener, Worcester, Mass., assignors to The Heald Machine Company, Worcester, Mass., a corporation of Massachusetts

Application June 25, 1934, Serial No. 732,238

32 Claims. (CL 51—95)

The present invention relates to a grinding machine for the successive reduction of a plurality of workpieces all to a predetermined size, and it is particularly applicable to a machine for grinding the internal surfaces of sleeves, bushings, or like articles.

In the copending Blood and Burns application, Serial No. 684,210, filed August 8, 1933, now U. S. Patent 2,027,627 dated January 14, 1936, the workpiece is positioned in a centerless work-supporting structure and is ejected therefrom, when completed, in response to the axial separation between the workpiece and the internal grinding wheel. This structure is entirely satisfactory in operation; however, when the machine is arranged for grinding tapered workpieces, such a machine involving either a turnable workhead or a turnable wheelhead, the mechanical elements for actuating the ejector are necessarily complicated. It is accordingly one of the principal objects of the present invention to avoid this objection by providing for fluid pressure actuation of the ejector, by which the workpiece is discharged from the work-supporting structure. By this arrangement, the work-supporting structure, as an entire unit, may be mounted for turning movement about a vertical axis to provide for grinding of tapered workpieces.

In the use of a gage mechanism of the type disclosed in the Kempston and Gallimore Patent No. 1,731,719, dated October 15, 1929, in connection with a centerless work-supporting structure from which the workpiece is discharged radially by an ejector, it is essential that the gage be fully retracted from the bore of the workpiece before the ejector begins its operation to avoid damage to the machine. It is accordingly a further object of the present invention to provide an interconnection between the gage retracting mechanism and the ejector to assure a positive withdrawal of the gage before the workpiece is discharged.

In order that the machine may be entirely automatic and operate satisfactorily on successive workpieces, there must be a definite and certain return of the ejector to original position to assure the positioning of an unground workpiece in the work-supporting structure before the grinding wheel is moved axially relative to the workpiece to bring said wheel into operative position. To this end, the present invention provides for an interlocking arrangement which provides for a relative axial movement of the grinding wheel into operative position at the beginning of a grinding operation only when the ejector has reached a predetermined position, thereby

assuring the positioning of an unground workpiece within the work-supporting structure.

Other and further objects and advantages of the invention will appear from the following detailed description taken in connection with the accompanying drawings in which:—

Fig. 1 is a front elevation of a machine embodying the invention.

Fig. 2 is a vertical sectional view substantially along the line 2—2 of Fig. 1, showing the work-supporting structure with the grinding wheel in operative position.

Fig. 3 is a fragmentary elevation through the workhead, showing the gage structure, with parts broken away to show more clearly the construction.

Fig. 4 is a vertical sectional view showing the driving means for the regulating wheel and the ejector actuating structure.

Fig. 5 is an end elevation of the structure of Fig. 4.

Fig. 6 is an enlarged elevation of the control mechanism mounted on the front of the machine.

Fig. 7 is a sectional view through the cross-feed mechanism.

Fig. 8 is a sectional view substantially along the line 8—8 of Fig. 4.

Fig. 9 is a fluid pressure diagram.

Like reference characters refer to like parts in the different figures.

Referring first to Fig. 1, the machine provides the usual reciprocating table 1 provided in an internal grinding machine; either the grinding wheel or the work to be ground is carried on said table, the reciprocations of the latter operating in either case to produce a relative translatory movement between said grinding wheel and the workpiece. In the construction shown, the table supports and carries a workhead 2 and the wheelhead 3 is mounted on a bridge 4 which spans the guideways, not shown, provided by the base 5 of the machine for the movements of the table 1. The grinding wheel 6 is carried on a spindle 7 journaled in the wheelhead 3 and is suitably rotated at a high rate of speed by any well-known mechanism, not shown. The workpiece a, Fig. 2, is mounted in the work-supporting structure on the workhead and is also rotated at a slow rate of speed, as will hereinafter appear.

The reciprocations of the table 1 which cause the rotating grinding wheel to make the desired traverse over the surface of a workpiece in the work-supporting structure are imparted in any well-known manner as by the use of fluid pres-

sure controlling and reversing mechanism, one type of which is described in the Heald and Guild Patent No. 1,582,468, dated April 27, 1926. It is sufficient to note, for the purpose of the present application, that reversal of the table is procured at each end of the normal working stroke by spaced adjustable dogs 8 and 9 Fig. 6, which are carried by blocks 10 and 11 adjustably mounted on the table 1 and which are adapted alternately to engage and move a reversing member 12. The latter provides spaced upwardly projecting lugs 13 and 14 (see Fig. 6) which, during the grinding operation, when the workpiece is reciprocated back and forth over the grinding wheel, are situated in a position to be engaged by the dogs 8 and 9 respectively. The movements of the member 12 procure reversal of the movements of the table 1 through suitable mechanism to be described later.

Referring now to Fig. 9, fluid under pressure, which is supplied by a pump 15, is directed through suitable valve mechanisms, hereinafter described, to the inlet port 16 of a casing 17 in which a reversing valve 18 is positioned. The valve casing 18 has outlet ports 19 and 20 connected by pipes 21 and 22 respectively to a port 23 in the right hand end of a cylinder 24, and a port 25 spaced from the left hand end of said cylinder, as indicated, for a purpose which will hereinafter appear. The cylinder is mounted within the base of the machine, and a piston 26 which is slidable within the cylinder has a projecting piston rod 27 which is secured to a depending lug 28 Fig. 4 on the under side of the table 1. The reversing valve 18 alternately directs fluid under pressure through the pipes 21 and 22 to the cylinder at opposite sides of the piston for urging the table 1 alternately to the right and to the left. At the same time, fluid exhausts from the opposite end of the cylinder through an exhaust port 29 in the casing 17.

The reversing member 12 is connected to the reversing valve 18 for actuating said valve in response to the shifting movements of said member. As best shown in Fig. 6, the forward end of the reversing valve 18 has secured thereto an arm 30 which supports a pin 31 in spaced relation to the center line of the valve. Said pin is positioned between spaced projecting lugs 32 and 33 on the end of an arm 34 secured to a shaft 35 journaled in the control box 36 on the front of the machine. The reversing member 12 is also secured against turning movement on the shaft 35 so that said member and the arm 34 move as a unit. The arm 34 has a V-shaped projecting portion 37 which engages with a corresponding V-shaped lug 38 on the end of an arm 39 pivotally mounted on a pin 40 carried by a bracket 41 secured within the control box. The arm 39 is urged upwardly into engagement with the V-shaped portion 37 by a spring 42.

As will be apparent from the drawings, the spacing between the lugs 32 and 33 is materially greater than the diameter of the pin 31 to provide a lost motion between the arm 34 and the reversing valve. As the arm 34 is rocked by either of the reversing dogs 8 or 9, the V-shaped portion 37 slides along the side of the V-shaped lug 38 with which it is in engagement until the points of the V-shaped portion and lug pass each other. The arm 34 is then moved positively through the remainder of its travel by the action of the spring 42 and shifts the valve 18. A positive reciprocation of the table is thus procured in

response to oscillation of the reversing member 12 by the reversing dogs 8 and 9.

For shifting the reversing valve manually in setting up the machine, the arm 34 carries a pin 43 which is positioned between spaced arms 44 and 45 provided by a plate 46. The latter is secured to a shaft 47 journaled in the control box and projecting through the cover 48, Fig. 1, of said box, carrying on the forward end thereof a lever 49 which provides for manual turning movement of the shaft. The arms 44 and 45 are spaced apart a distance substantially greater than the diameter of the pin 43 to permit the arm 34 to rock without a corresponding movement of the lever 49, during the automatic operation of the machine.

The crossfeed movement between the workpiece in the workhead and the grinding wheel is obtained by transverse movement of the wheelhead 3 on the bridge 4. The wheelhead is mounted on a cross-slide, not shown, and movement of said cross-slide is obtained by rotation of a crossfeed screw 50, Fig. 7, which engages an internally threaded portion, not shown, of the cross-slide. Said crossfeed screw carries a ratchet wheel 51 secured against turning movement thereon, the latter being in a position for engagement with oppositely acting pawls 52 and 53 carried on studs 54 and 55 on an annular member 56 journaled on the crossfeed screw. 30

During the crossfeed movement of the grinding wheel, which is procured by a positive clockwise rotation (Fig. 1) of the annular member 56 through mechanism hereinafter described, the pawls are carried clockwise with said member, 35 and the pawl 53 procures a positive rotation of the crossfeed screw. As the grinding operation continues, a pin 57 on the pawl 52 is brought into engagement with a shield 58 adjustably positioned in the casing 59 in which the crossfeed mechanism is located. Said shield procures retraction of the pawl 52 from the ratchet wheel 51, but the crossfeed movement continues under the action of pawl 53 until the grinding is completed. During a subsequent retraction of the 45 crossfeed movement by a counterclockwise turning movement of the annular member 56, the latter turns through a greater distance than the ratchet wheel since the pawl 52 is inoperative until the pin on said pawl moves out of engagement with the shield 58. The pawl 52 then being moved into engagement with the ratchet wheel by a spring 60, procures rotation of the ratchet wheel 51 during the remainder of the counterclockwise movement of the annular member 56, 55 thus retracting the grinding wheel from its advanced position. The relative turning movement between the annular member 56 and the ratchet wheel 51 during the retracting movement provides a compensation for the reduction in size of 60 the grinding wheel, this compensation, as will be apparent, being substantially equal to the actual reduction of the grinding wheel.

For the fluid pressure actuation of the crossfeed mechanism, the annular member 56 has an integral pinion 61, Figs. 1 and 7, which is engageable with a vertical rack 62 on the upper end of a piston rod 63 secured to a piston 64 slidable in a cylinder 65 secured to the base of the machine. A roll 66, Fig. 1, holds the rack in engagement with said pinion. 70

Fluid under pressure from the pump 15 passes through a pipe 67 (Fig. 9), to a channel 68 in a valve casing 69, the latter having a longitudinal bore 70 in which a valve member 71 is slidable. 75

The channel 68 intersects the bore 70 at a point substantially opposite to the intersection of a channel 72 with said bore. The latter channel is connected by a pipe 73 to a port in the lower end of the cylinder 65, said pipe 73 preferably having a manually adjustable throttle valve 74 therein for controlling the rate of crossfeed movement.

The upper end of the cylinder 65 is connected by a pipe 75 and a pipe 76 connecting therewith to a channel 77 in the casing 69. Said channel 77 also intersects the longitudinal bore 70 and fluid connection is normally provided from said channel to an exhaust channel 78 in the casing 69 by a reduced portion 79 of the valve member 71 adjacent the right hand end thereof. As fluid under pressure passes into the lower end of the cylinder 65, the upward movement of the piston procures a corresponding clockwise movement of the annular member 56 for a crossfeed movement of the grinding wheel, fluid from above the piston exhausting at this time through the pipe 75 to the exhaust channel. The retraction of the grinding wheel by a downward movement of the piston is procured by directing fluid under pressure to the upper end of said cylinder, as will hereinafter appear.

The function and shifting movements of the valve 71, so far as it controls the movements of the table, are fully described in the copending Blood and Burns application, Serial No. 681,334, filed July 20, 1933, now U. S. Patent 2,011,705, dated August 20, 1935. For the purposes of the present application, it will be sufficient to note that the casing 69 (Fig. 9) has a channel 80 spaced from the channel 68 and connected by a pipe 81 to a channel 82 in a casing 83 having a longitudinal bore 84 therein in which the main throttle valve 85 is positioned. The latter has a longitudinal recess 86 therein which is open to the inner end of the bore 84 and the end of said bore is connected by a pipe 87 to the inlet port 16 in the reversing valve casing 17. The throttle valve 85 has a triangular notch 88 adjacent to the intersection of the channel 82 with the bore 84 to provide fluid connection between said channel 82 and the recess 86 in the valve. The triangular shape of the notch 88 provides for throttling the flow of fluid to the table cylinder by adjusting the angular position of said throttle valve. With the valve 71 in the position shown, fluid connection is provided between the channel 68 and the channel 82 by the reduced portion 89 of the valve 71 between the full-sized portions 90 and 91 thereof.

For retraction of the cross-feed movement the valve 71 has a channel 92 therein which is open at one end to the reduced portion 89 of said valve and at the other end intersects with an annular groove 93 formed in the full-sized portion 91 of said valve. When the valve 71 is shifted into its right hand position at the end of the grinding operation by mechanism hereinafter described, fluid under pressure from the channel 68 passes through the channel 92 into the groove 93, which is then in alignment with the opening into the channel 77, thereby directing fluid under pressure through the pipe 76 and the connecting pipe 75 into the upper end of the cylinder 65 to procure a downward movement of the piston 64 and a corresponding retraction of the crossfeed movement.

The pipe 76, forming part of the connection to the upper end of the cylinder 65, is connected to a port 94 in the upper end of a casing 95 in

which a valve 96 is positioned, the latter being normally retained in its upper position, shown by a spring 97. The casing 95 also has a port 98 spaced from the port 94 and connected by a short pipe 99 to the pipe 73 which is connected to the lower end of the cylinder 65. The flow of fluid from the pipe 99 to an exhaust port 100 in the casing 95 is cut off by the valve 96 during the crossfeed movement. As fluid under pressure enters the upper end of cylinder 65 for retracting the crossfeed movement, fluid under pressure also enters the upper end of the casing 95 and moves the valve 96 downwardly to provide an exhaust connection between the ports 98 and 100 for fluid from the lower end of the cylinder 65.

The workpiece *a* is supported in a centerless work-supporting structure mounted on the table 1. As shown in Figs. 2 and 4, the workhead 2 has a spindle 101 journaled therein, and a regulating wheel 102 of large diameter is carried on the inner or right hand end thereof for engagement with the periphery of the workpiece *a*, as best shown in Fig. 2. Forwardly of the regulating wheel 102, and in the same vertical plane, is positioned a work-supporting wheel 103 mounted on a slide 104 adjustable on a bracket 105 secured to the table, said wheel also engaging with the periphery of the workpiece. An adjusting screw 106, which is held against axial movement in a lug 107 on the bracket 105, engages the slide 104 to provide for adjustment of the position of the supporting wheel relative to the regulating wheel. The workpiece *a* is held in engagement with the regulating and supporting wheels by a pressure wheel 108 on a shaft 109 in the end of an arm 110 which is secured against rotation on a shaft 111 journaled in the workhead, said pressure wheel being resiliently held against the workpiece, as will hereinafter appear. The spindle 101 is positively rotated by a driving motor, not shown, connected by V-belts to a pulley 113 on said spindle. Rotation of the wheel 102 procures a corresponding rotation of the workpiece *a* by engagement with the periphery thereof, this rotation of the workpiece being clockwise as seen in Fig. 2. The workpiece is thus supported and rotated on the cylindrical outer surface thereof during the grinding operation.

As shown in Fig. 3, the workpiece is held against axial movement by a rotating backing plate 114 which is rotatable about an axis coinciding substantially with the axis of the workpiece, and which is supported by bearing surfaces 115 forming a part of the workhead. The backing plate has a cylindrical flange 116 which engages with the end surface of the workpiece, the latter being urged axially against said flange by the action of the pressure wheel 108, whose axis extends at a slight angle to the axis of the workpiece.

The grinding operation is under the control of a gage member 117, Fig. 3, which is carried on the end of a gage rod 118 longitudinally slidable in the workhead. The gage rod extends through an opening 119 centrally of the backing plate 114 so that the gage member 117 is supported in alignment with the bore of the workpiece. The outer or left hand end of the gage rod 118 has an arm 120 journaled thereon, said arm being supported against axial movement by bearing members 121. The lower end of said arm is secured against movement on the end of a rod 122 which is longitudinally slidable in a bore 123 in the workhead. The right hand end of the rod 122 projects to the right beyond the

workhead, as shown in Fig. 1, and is normally in alignment with the head of an adjustable screw 124 mounted in a bracket 125 on the bridge 4. A spring 126 in an opening 127 within the 5 workhead surrounds the rod 122 and engages, at one end, with a sleeve 128 on said rod, said sleeve being suitably held against movement on said rod. The other end of said spring engages a portion of the workhead for normally urging the 10 rod 122, which is parallel to the gage rod 118, to the right, thereby urging the gage 117 against the end of the workpiece.

The rod 122 supports a forwardly projecting arm 129 adjacent the arm 120, and an adjustable 15 screw 130 is held in adjusted position in the outer end of said arm by a locking nut 131. At the beginning of the grinding operation, before the workpiece is sufficiently large to permit entry of the gage, the right hand movement of the screw 20 130 relative to the workhead is limited by engagement of said gage with the end of the workpiece. When the bore of the workpiece is sufficiently enlarged by the grinding operation, the gage 117 enters said bore, providing an extended 25 movement of the screw 130 to the right for procuring a run-out of the table to the position of Fig. 1, as will hereinafter appear.

The control mechanism, by which the movements of the table are procured, may be of the 30 type fully disclosed in the above cited copending application of Blood and Burns, Serial No. 681,334, filed July 20, 1933. It is sufficient to note for the purpose of the present invention that, as best shown in Figs. 1 and 6, a lever 132, 35 which is journaled on a shaft 133 positioned in the control box 36 has a depending arm or latch 134 which normally engages a notch 135 provided in a lug 136 on a depending arm 137 journaled on a shaft 138 in the control box. Said arm is urged counterclockwise by a spring 40 139 which is positioned in a recess 140 in a bracket 141 mounted in the control box, one end of said spring engaging the inner end of the recess and the other end of said spring engaging 45 said arm. A bell crank lever 142 which is journaled on the shaft 138 has a depending arm 143 which engages a pin 144 on the arm 137. The other arm 145 of the bell crank lever 142 projects upwardly between the lugs 13 and 14 50 on the reversing member 12 and is provided with a cam surface for engagement with the reversing dog 9 which is pivotally mounted on a pin 146 in the block 11.

The lever 132 has an upwardly extending arm 55 147 which projects through an opening 148 in the control box. The table 1 carries a block 149, Fig. 1, which supports a pin 150 on which a bell crank lever 151 is pivotally mounted. The latter is received within a slot 152 in said block and is 60 held frictionally against unintended movement therein. One arm 153 of the lever 151 extends substantially horizontally to the right and slightly above the upper end of the arm 147 and the opposite arm 154 of said lever extends upwardly into horizontal alignment with the adjustable screw 130 connected to the gage mechanism. During the grinding operation, the adjustable screw 130 does not move sufficiently to the right to engage and rock the lever 151. 70 When the gage 117 enters the workpiece, however, the extended movement of the screw 130 resulting from said entry turns the lever 151 clockwise and moves the end of the horizontal arm 153 thereof downwardly into alignment with 75 the end of the arm 147.

On the subsequent movement of the table 1 to the right, after the rocking of the lever 151, said lever engages and rocks the lever 132, thereby releasing the arm 137 to permit movement thereof to the right for elevating the upwardly 5 extending arm of the bell crank lever 142. Said arm in its upper position is in alignment with the reversing dog 9 and prevents engagement between said dog and the reversing member during movement of the table to the left so that the 10 table moves to the inoperative position of Fig. 1, to withdraw the grinding wheel from the work-piece.

The arm 137 engages at its lower end in a notch 155 provided by the valve 71, and the 15 swinging movement of said arm to the right, shifts said valve for procuring a retraction of the crossfeed movement, as well as other movements which will be hereinafter described. The valve movement to the right establishes fluid 20 connection from the pump 15 to the upper end of the cylinder 65, as above pointed out, and the crossfeed movement is automatically retracted.

The above mechanism is all clearly disclosed 25 in the patents and applications above referred to, and is not of itself a feature of the present invention, the description having been incorporated herein for clarifying the operation of the novel mechanism hereinafter disclosed, and for dis- 30 closing a completely automatic machine. The hereinafter described structure, which is an embodiment of the present invention, operates in connection with the foregoing or similar mechanism in attaining the novel results above set 35 forth.

Referring now to Fig. 9, the shifting movement of the valve 71 at the end of the grinding operation also procures a retraction of the gage member from within the bore of the finished 40 workpiece. The workhead (see Fig. 3) is provided with a longitudinal bore 156 in which a piston 157 is movable. A piston rod 158 projects to the left beyond the workhead and engages the head of an adjustable screw 159 in the arm 120 45 of the gage mechanism. The piston 157 is normally urged to the right by a spring 160 surrounding the piston rod. The right hand end of the bore 156 has a port 161 connected by a pipe 162, Fig. 9, to a port 163 in a casing 164. A piston 50 valve 165 is vertically movable within said casing and is normally held in the lower position shown by a coil spring 166 engaging the end of said valve. A port 167 in said casing, in alignment with the port 163, is connected by a pipe 168 to 55 the pipe 76 which extends between the valve 71 and the upper end of the cylinder 65. As fluid under pressure is directed into the upper end of the cylinder 65 for the crossfeed retraction at the end of the grinding operation, fluid under 60 pressure also passes through the pipes 168 and 162 into the bore 156, urging the piston therein to the left and retracting the gage from within the bore of the workpiece, since the valve 165 has a reduced portion 169 which provides a fluid con- 65 nection at all times between the ports 163 and 167.

During the runout of the table to rest position at the completion of the grinding operation, the finished workpiece or workpieces are removed 70 from operative position and unground workpieces are positioned therein. As shown in Figs. 2 and 4, the spindle 101 which carries the regulating wheel 102 is hollow for the reception of a shaft 170 journaled therein. The latter carries on the 75

forward end thereof a plate 171 secured against movement thereon, and said plate has an ejector arm 172 which extends transversely across the surface of the wheel 102 in spaced relation thereto, the arm being normally beneath the workpiece *a* as shown in Fig. 2. The plate 171 has a slot 173 therein which receives the end of the shaft 170, a clamping nut 174 on the end of the shaft 170 supporting the plate in adjusted position thereon. The left hand end of the shaft 170 has a fluid motor 175 connected thereto, as will hereinafter appear, for actuating said ejector arm, said motor procuring, during the runout of the table to rest position, a turning movement of the shaft 170 for a clockwise rotation (Fig. 2) of the ejector arm into the dot-dash line of Fig. 2. During this movement, the upper surface of the arm 172 engages the workpiece in the work-supporting structure and carries it around the periphery of the regulating wheel 102 to the top thereof where it is discharged toward the rear of the machine.

Referring again to Figs. 4 and 5, the shaft 170 carries a cam 176 which engages with a roller 177 on one end of a lever 178 journaled on a pin 179 secured to the workhead. The opposite end of the lever 178 has a flat surface 180 which engages with one arm of a bell crank lever 181 journaled on the outer or left hand end of the shaft 111 to which the arm 110 carrying the pressure wheel 108 is secured. The opposite arm 182 of the bell crank lever extends upwardly between the opposite legs 183 and 184 of a U-shaped member 185 secured against turning movement on the shaft 111. Set screws 186 and 187, which are positioned in the legs 183 and 184, engage opposite sides of the arm 182 to provide for adjustment of the bell crank lever 181 relative to the member 185.

A rod 188, Figs. 1 and 5, extends upwardly from a lug 189 on the workhead through a notch, not shown, in the end of the bell crank lever 181. A spring 190 surrounds the rod and engages with the upper surface of the bell crank lever to maintain the latter in engagement with the surface 180. The upper end of the spring 190 engages a threaded sleeve 191 on the upper threaded end of the rod 188. Turning movement of the sleeve 191 adjusts the tension of the spring 190, thereby varying the downward pressure on the bell crank lever 181 and accordingly adjusting the pressure exerted by the pressure wheel 108 against the workpiece. During turning movement of the shaft 170 for ejecting the workpiece, the cam 176 on said shaft rocks the lever 178 to procure a clockwise movement (Fig. 5) of the bell crank lever 181 and a corresponding retraction of the pressure wheel 108 (counterclockwise, Fig. 2) from engagement with the workpiece, permitting the workpiece to be easily elevated by the ejector from within the work-supporting member.

As shown in Fig. 2, the table 1 has an upwardly extending portion 192 on which a bracket 193 is mounted, the latter having parallel slots 194 which are engaged by bolts 195 to permit adjustment of said bracket relative to the table. The bracket 193 provides a U-shaped groove 196, Fig. 1, having a bottom surface 197 inclined downwardly toward the rear, the rearward end of the surface 197 being in substantially vertical alinement with the forward surface of the regulating wheel 102 to permit workpieces positioned in the U-shaped groove 196 to drop into the work-supporting member. The bracket 193 also provides an arcuate U-shaped groove 198 substantially

parallel to the periphery of the wheel 102 and in alinement with the workpiece *a* in the work-supporting member, said groove extending from a point slightly above the workpiece to a point directly above the upper position of the ejector arm and intersecting the groove 196. 5

The workpieces in the groove 196 are normally urged by gravity toward the rear of the machine into the position shown in Fig. 2 and are prevented from passing beyond the position shown 10 by an arm 199 which engages the bracket 193 in alinement with the workpieces in the groove 196. The arm 199 is secured against rotation on a shaft 200 journaled in a bracket 201, mounted on the workhead and said shaft has a 15 horizontally extending arm 202 which engages the upper end of a vertical plunger 203 in a sleeve 204 provided by the bracket 201. A cam 205 secured to the shaft 170 adjacent the plate 171 engages, during the rotation of the shaft 170, 20 with the lower end of the plunger 203, urging the latter upwardly to procure a clockwise turning movement of the arm 199, for releasing the rearmost workpiece in the groove 196. A depending arm 206 secured to the shaft 200 engages a 25 spring 207 which is positioned between the sleeve 204 and said arm 206 and which retains the arm 199 in the normal position shown.

The ejector arm 172, as shown in Figs. 2 and 4, is of a sufficient width to prevent the rearmost 30 workpiece *a'* in the groove 196, when released by the arm 199, from dropping between the groove 198 and the wheel 102 beneath said ejector arm. As the ejector arm returns counterclockwise to the position shown in full lines in Fig. 2, this 35 movement occurring before the workhead begins its movement into operative position for a subsequent grinding operation, as will hereinafter appear, the workpiece *a'* follows said arm downwardly, guided by the groove 198 and the ejector 40 arm so that said workpiece is properly positioned in the work-supporting member in readiness for a grinding operation thereon.

As above stated, the finished workpiece is discharged when the ejector reaches the dot-dash 45 line position of Fig. 2. From this position, the finished workpiece rolls by gravity toward the rear of the machine over a downwardly and rearwardly inclined surface 208 provided by a rearwardly extending portion 209 of the bracket 201. 50

The fluid pressure motor which actuates the ejector is actuated by fluid from the main table cylinder and is operable only when the gage member has been completely retracted from the workpiece. As best shown in Fig. 8, the left hand 55 end of the shaft 170 has secured thereto the piston or vane 210 of the oscillatory fluid motor 175, said vane oscillating in a semi-cylindrical opening 211 in a casing 212 secured, as shown in Fig. 4, to the workhead. Said casing 212 has a channel 213 which intersects the opening 211 adjacent the top thereof, said channel being connected by a pipe 214 to a port 215 in the bore 156. The port 215 is spaced longitudinally from a port 216 which is connected by a pipe 217 to a port 218 65 in the valve casing 164. Fluid connection between the ports 215 and 216 is cut off when the piston 157 is in its normal right hand position; when said piston moves to the left for gage retraction, the reduced portion 219 of said piston permits fluid 70 under pressure to enter the motor 175.

Directly above the reduced portion 169 of the valve 165 is a full-sized portion 220 which prevents fluid connection between the port 167 and an adjacent port 221, the latter being connected 75

by a pipe 222 to the pipe 22, which admits fluid under pressure to the table cylinder at the left of the piston. Directly above the port 221 and axially spaced therefrom, is a port 223 connected by a pipe 224 to a port 225 connecting with the extreme left hand end of the table cylinder. The casing 164 also has a port 226 opposite to, but spaced axially of said casing from the port 221. Fluid connection between the ports 221 and 226 10 is normally prevented by spaced full-sized portions 227 and 228 on the piston valve, the latter full-sized portion also preventing fluid connection between the port 226 and the port 223, above referred to. Fluid connection between the ports 218 and 223 is normally prevented by spaced full-sized portions 229 and 230 on the valve 165. When the valve 165 is moved into its upper position, fluid connection is provided between the ports 221 and 226 and also between the ports 218 15 and 223, for a purpose which will hereinafter appear. The port 226 is connected by a pipe 231 to a channel 232 intersecting the chamber 211 adjacent the lower portion thereof for admitting fluid to said chamber.

25 When fluid under pressure is directed through the pipe 168 into the casing 164, the fluid pressure in said casing moves the valve 165 upwardly to establish fluid connection between the left hand end of the table cylinder and the port 216 through the pipes 217 and 224. At the same time the fluid under pressure in the pipe 162 moves the piston 157 to the left and establishes fluid connection directly from the table cylinder through the port 216 to the channel 213 in the 30 ejector motor. At this time the left hand end of the table cylinder is connected to the exhaust port 29 through the pipe 22. When the piston 26 closes the port 25, during movement of the table to the left, a further movement of the table 35 builds up a pressure in the left hand end of the table cylinder which is sufficient to procure a turning movement of the vane 210, the latter being connected through the pipes 214, 217 and 224 to the table cylinder. Clearly, the quantity 40 of fluid remaining in the left hand end of the cylinder after the port 25 is closed, is necessarily more than sufficient to oscillate the vane from the normal position shown, into its opposite end position, shown in dotted lines in Fig. 8.

45 50 When the vane 210 reaches its lower or dot-dash line position of Fig. 8, the ejector at this time being in the raised (dot-dash line) position of Fig. 2, the fluid under pressure in back of the vane passes through a by-pass channel 233 and a spring controlled valve 234 into the pipe 231, thus allowing fluid to discharge from the left hand end of the table cylinder 24 for a slight additional movement of the table to the left after the ejector reaches its upper position, at which 55 time a dog 235 carried on the table engages and actuates the reversing member 12. Said dog, as best shown in Fig. 6, has a cam surface 236 engageable with the upper end 145 of the bell crank lever 142 for depressing the latter sufficiently to permit said dog to engage the lug 14 on the reversing member.

60 Reversal of the valve 18 directs fluid under pressure through the pipes 222 and 231 into the lower portion of the fluid motor 175. The valve 70 65 75 234 now being closed, fluid under pressure beneath the vane 210 swings said vane upwardly, the fluid from above said vane discharging through the pipes 214, 217 and 224 into the left hand end of the table cylinder for moving the table to the right. When the vane 210 reaches

its uppermost position, fluid under pressure passes through a by-pass channel 237 and past a spring-pressed valve 238, thus permitting fluid under pressure to enter the left hand end of the table cylinder until the piston 26 therein uncovers the port 25. Thereafter, the movements of the piston 26 are controlled by fluid under pressure in the pipes 21 and 22 in the usual manner.

During the return of the table to operative position, a depending dog 239 pivoted on a pin 240 on a block 241 on the front of the table engages the upper end of the bell crank lever 142, moving the latter downwardly and the arm 137 counterclockwise to return the valve 71 to its original position, the latch 134 engaging in the notch 135 15 to hold the arm 137 in position. The return of the valve 71 to its original position cuts off the flow of fluid under pressure to the upper end of the crossfeed cylinder 65 and also allows the valve 96 to return to its normal upper position. When the valve 96 returns to its upper position, fluid under pressure is directed to the underside of the piston 64 for a crossfeed movement of the wheel relative to the workpieces. The return of the valve 71 to original position also cuts off 25 the flow of fluid under pressure to the underside of the valve 165, to allow said valve to return to its lower position. This movement of the valve permits the piston 157 to be returned to the right for releasing the gage so that the latter may 30 operate in the usual manner during the subsequent grinding operation.

As best shown in Fig. 1, the bell crank lever 151 is reset to its original position, when the table reaches the end of its movement to the left, by 35 a bracket 242 secured to the control box 48, said bracket having a flat upper surface engaging with the arm 153 of said lever, turning said lever counterclockwise in readiness for actuation thereof during the subsequent grinding operation.

The operation of the machine, which will be clear from the foregoing description, will be briefly summarized. With the table in the position of Fig. 1, this being its position at the end 45 of the movement thereof to the left, the ejector is in the upper position of Fig. 2, and the dog 235 has just actuated the reversing member 12 for returning the table to operative position. At this time, the valve 71, Fig. 9, is in its right hand 50 position providing fluid connection from the pump to the under side of the valve 165, the latter being in its raised position. The vane 210 at this time is in the dot-dash line position of Fig. 8. Fluid under pressure passing the reversing valve 18, the latter being in the position of Fig. 9, enters the ejector motor 175 through the pipe 231, thereby returning the ejector to its original position, and at the same time procuring a movement of the table to the right. As this 55 movement continues, and after the ejector vane 210 reaches its upper position, fluid under pressure passes the valve 238 and enters the left hand end of the table cylinder until the port 25 is uncovered, fluid under pressure then passing 60 through the pipe 22 for continuing the movement of the table. Thereafter, during the movement of the table to the right, the dog 239 returns the bell crank lever 142 and the arm 137 to the original position of Fig. 1 in readiness for 65 the subsequent grinding operation, said dog also resetting the valve 71 through the arm 137.

As the table approaches operative position with the grinding wheel located within the bore of the workpiece, the reversing dogs 8 and 9 be- 70 75 75

come operative for controlling the reciprocations of the table. The crossfeed movement which was initiated when the valve 11 was reset by the dog 238 advances the grinding wheel against the surface of the workpiece for a cutting operation which continues until the workpiece is sufficiently large to permit entry of the gage 117 within the bore thereof.

When the gage enters the workpiece, the amplified right hand movement thereof swings the bell crank lever 151, moving the end of said lever into alignment with the lever 132, so that during the subsequent right hand movement of the table, said lever releases the arm 137 and the latter moves to the right into the position of Fig. 6. This movement procures an extended movement of the table to the left by rendering inoperative the dog 9, and also procures, as above pointed out, a retraction of the crossfeed movement. As the table begins its extended movement to the left, fluid under pressure enters the bore 156 in back of the piston 157 for retracting the gage from within the bore of the workpiece. After the gage is fully retracted, fluid connection is provided between the left hand end of the cylinder and the upper end of the ejector motor 175. When the table piston 26 has closed the port 25 during the table movement to the left, the fluid to the left of said piston discharges into the upper end of the ejector motor and swings said vane downwardly, thereby raising the ejector for discharging the finished workpiece. As the ejector begins its upward movement, the pressure roll 108 is retracted, as above indicated, and when the ejector reaches its uppermost position, an unground workpiece is released.

When the ejector reaches its upper position, the vane 210 being then in its lowermost position, fluid from the left hand end of the table cylinder is allowed to discharge through the by-pass channel 233, and the slight additional left hand movement of the table provided thereby permits the dog 239 to actuate the reversing valve. The grinding operation is then repeated in the manner above outlined. It will be noted that the fluid remaining in the left hand end of the cylinder after the port 25 is closed is always slightly more than the amount of fluid required for actuating the ejector motor to assure movement of the ejector arm through its entire cycle, thus making certain the discharge of the ground workpiece and the insertion of an unground workpiece while the wheel is spaced axially from the work-supporting structure and while the gage is out of alignment with the work.

From the foregoing, it will be apparent that the present invention provides for a positive actuation of the ejector by fluid under pressure and is so interconnected with the table actuating mechanism that the ejector must move through its predetermined cycle before the table can be reversed for returning said table to operative position for a subsequent grinding operation. In addition, the ejector motor and the gage mechanism are interconnected to prevent operation of the ejector while the gage is within the bore of the workpiece, thus avoiding jamming of the machine and damage to the gage mechanism. It will be noted that, if the gage is not retracted, the table will be brought to rest during its movement to the left by fluid trapped in the left hand end of the cylinder, the only escape for fluid, after the port 25 is closed by the piston, being into the ejector motor, fluid connection to said motor being provided only when the gage is fully retracted.

We claim,

1. In a grinding machine, a grinding member and a work-supporting member, a table on which one of said members is mounted, a gage member adapted to enter the workpiece when the latter reaches the desired size, means under the control of said gage for procuring a movement of said table for axial separation between said members, means for procuring a radial discharge of a workpiece from the work-supporting member, fluid pressure means for actuating said discharging means, means for withdrawing the gage from within the bore of the workpiece and means providing for operation of said fluid pressure means only after the gage is withdrawn from within the bore of the workpiece.

2. In a grinding machine, a grinding member and a work-supporting member, a table on which one of said members is mounted, a gage member adapted to enter the bore of a workpiece in the work-supporting member when the latter reaches the desired size, means under the control of said gage for procuring a movement of said table for axial separation between said members, means for procuring a radial discharge of a workpiece from the work-supporting member, means for withdrawing the gage from within the bore of the workpiece and means providing for the operation of said discharging means only after the operation of said withdrawing means by which the gage is withdrawn from the bore of the workpiece.

3. In a grinding machine, a grinding member and a centerless work-supporting member, means governed by the progress of the grinding operation for procuring an axial separation between said members when a workpiece in the work-supporting member reaches the desired size, an ejector, and fluid pressure means responsive to and automatically operable during the axial separation for actuating said ejector.

4. In a grinding machine, a grinding member and a centerless work-supporting member, a table on which one of said members is mounted, means governed by the progress of the grinding operation for procuring a movement of the table for an axial separation between said members when a workpiece in the work-supporting member reaches the desired size, an ejector, and fluid pressure means responsive to said table movement and automatically operable during the axial separation for actuating said ejector.

5. In a grinding machine, a grinding member and a centerless work-supporting member, a table on which one of said members is mounted, a fluid pressure motor for actuating said table, means for procuring a movement of the table for an axial separation between said members, an ejector operable during the axial separation, and fluid pressure means connected to the table motor and actuated by the exhaust fluid from said table motor for actuating the ejector.

6. In a grinding machine, a grinding member and a centerless work-supporting member, fluid pressure means governed by the progress of the grinding operation for procuring an axial separation between said members when the workpiece in the work-supporting member reaches the desired size, an ejector for procuring a radial discharge of the workpiece from the work-supporting member and fluid pressure means connected to said first fluid pressure means and actuated by the exhaust fluid therefrom for actuating said ejector.

7. In a grinding machine, a grinding member and a centerless work-supporting member, the

- latter comprising a rotatable regulating wheel engageable with the periphery of a workpiece in said supporting member and a work-support, an ejector for procuring a radial discharge of the workpiece from the supporting member, size controlling means engageable with the bore of the workpiece for controlling the grinding operation, means under the control of said size determining means for procuring operation of the ejector, means for withdrawing the size determining means from the bore of the workpiece, and means providing for operation of the ejector only after the operation of said withdrawing means.
15. In a grinding machine, a grinding member and a centerless work-supporting member, a table on which one of said members is mounted, an ejector for procuring a radial discharge of a workpiece from the supporting member, sizing means engageable with the bore of the workpiece for controlling the grinding operation, means under the control of said sizing means for procuring movement of the table for an axial separation between said members, means responsive to the table movement for actuating the ejector, means for removing the sizing means from within the bore of the workpiece and means associated with the sizing means to provide for the operation of the ejector only when the withdrawing means have fully withdrawn the sizing means from the bore of the workpiece.
9. In a grinding machine, a grinding member, a work-supporting member, an ejector for procuring discharge of a workpiece from within the work-supporting member, size determining means engageable with the bore of the workpiece, means for withdrawing the size determining means from within the bore of the workpiece, means for actuating the ejector, and means associated with said withdrawing means to provide for operation of the ejector actuating means only after the withdrawing means have fully withdrawn the size determining means from the bore of the workpiece.
10. In a grinding machine, a grinding member, a work-supporting member, an ejector for procuring discharge of a workpiece from within the work-supporting member, size determining means engageable with the bore of the workpiece, means under the control of said size determining means for procuring operation of the ejector, means for withdrawing the size determining means from within the bore of the workpiece, and means providing an interconnection between said withdrawing means and said actuating means to provide for operation of the ejector operating means only after the withdrawing means have fully withdrawn the size determining means from within the bore of the workpiece.
11. In a grinding machine, a grinding member, a work-supporting member, an ejector for procuring discharge of a workpiece from within the work-supporting member, size determining means engageable with the bore of the workpiece, means under the control of said size determining means for procuring operation of the ejector, means for withdrawing the size determining means from within the bore of the workpiece, and means providing an interconnection between said withdrawing means to provide for operation of the ejector operating means only after the withdrawing means have fully withdrawn the size determining means from within the bore of the workpiece.

drawn the size determining means from within the bore of the workpiece.

12. In a grinding machine, a grinding member and a work-supporting member, a table on which one of said members is mounted, said table procuring a relative axial movement between said members, an ejector for removing a finished workpiece from the work-supporting member, size determining means, means under the control of said size determining means for procuring movement of the table for an axial separation between said members, fluid pressure means for actuating the ejector while said members are separated, means for withdrawing the size determining means from engagement with the workpiece, and means associated with said withdrawing means to provide for operation of said fluid pressure means only when the size determining means are out of engagement with the workpiece. 20

13. In a grinding machine, a grinding member and a work-supporting member, a table on which one of said members is mounted, said table procuring a relative axial movement between said members, fluid pressure means for actuating said table, an ejector for removing a finished workpiece from the work-supporting member, fluid pressure means for actuating the ejector, and means providing a connection between the table actuating means and the ejector 30 actuating means for directing exhaust fluid from the table motor to the ejector motor for actuating the latter.

14. In apparatus of the class described, a fluid motor comprising a piston and cylinder, means for directing fluid under pressure alternately to opposite sides of said piston for actuating the same, a second fluid motor, and means controlled by the position of the piston for directing the exhaust fluid from one side of the piston during 40 a predetermined portion of its stroke to said second motor for actuating the latter during movement of the piston within the cylinder.

15. In apparatus of the class described, a fluid motor comprising a piston and cylinder, means for directing fluid under pressure alternately to opposite sides of said piston for actuating the same, a second fluid motor, means connecting one end of said cylinder to said second fluid motor, means controlled by the position of the piston for cutting off the exhaust of fluid from said cylinder before the piston therein reaches the end of its stroke for directing the exhaust fluid during the remainder of said stroke to said second fluid motor for actuation of the latter 55 during a predetermined portion of the piston movement, and means operative upon reversal of said second fluid motor for directing the exhaust fluid from said second motor to said first motor for actuating the latter. 60

16. In apparatus of the class described, a fluid motor comprising a piston and cylinder, valve means for directing fluid under pressure to said cylinder alternately at opposite sides of the piston for actuating the latter, said valve means 65 being shifted in response to movement of the piston within the cylinder, a second fluid motor, means for directing the exhaust fluid from the first motor to said second motor for actuating said second motor during a portion of the piston movement as the latter reaches the end of its stroke, and means operative upon reversal of said valve means for directing the exhaust fluid from said second motor to said first motor for actuating the latter. 75

17. In apparatus of the class described, a fluid motor comprising a piston and cylinder, means for directing fluid under pressure alternately to opposite sides of said piston, including a port in the cylinder spaced from one end thereof, a second fluid motor, means connecting said one end of the cylinder to said second fluid motor for actuation of the latter by the exhaust fluid in the first motor after the piston therein has closed the port, and means operative upon reversal of said second fluid motor for directing the exhaust fluid from said second motor to said first motor for actuating the latter.
18. In apparatus of the class described, a fluid motor comprising a piston and cylinder, valve means for directing fluid under pressure alternately to opposite sides of the piston for movement thereof relative to the cylinder, said valve means being reversed at opposite ends of the piston stroke in response to movement of said piston, a second fluid motor including a piston and cylinder, means for actuating said second motor by the exhaust fluid from one side of the piston of the first motor during a portion of the movement of the latter piston as it reaches the end of its stroke, and means operative upon reversal of said valve means for directing exhaust fluid from said second motor to said first motor for actuating the latter.
19. In apparatus of the class described, a fluid motor comprising a piston and cylinder, means for directing fluid under pressure alternately to opposite sides of the piston for movement thereof relative to the cylinder, a second fluid motor including a piston and cylinder, means for actuating said second motor by the exhaust fluid from one side of the piston of the first motor, means operative upon reversal of said first motor for directing exhaust fluid from said second motor to said first motor for actuating the latter, and a by-pass in said second motor to provide for discharge of fluid through said motor for a continued movement of said first motor when the piston of the second motor reaches the end of its stroke.
20. In apparatus of the class described, a table having operative and an inoperative position, a fluid motor including a cylinder and piston for actuating said table, means responsive to the table movement for reversing the flow of fluid to said cylinder, a second fluid motor, means operative during the movement of the table into inoperative position for directing exhaust fluid from said first motor to said second motor for actuating the latter, and means operative on reversal of the table movement for directing fluid under pressure to said second motor and for directing the exhaust fluid from said second motor to the first motor for actuating the latter.
21. In a grinding machine, a grinding member and a work-supporting member, a table for one of said members, movement of said table procuring an axial separation between said members, a fluid motor for said table, means responsive to the movement of said table for reversing the direction of movement thereof, an ejector for workpieces in said work-supporting member, a fluid motor for actuating said ejector, means responsive to movement of the table for actuating said ejector, means operative upon reversal of the table movement for procuring a return of the ejector to original position, said fluid motors being interconnected to provide for a return of the ejector before the table returns to operative position with the grinding member engaging with a workpiece in the work-supporting member.
22. In a grinding machine, a grinding member, a centerless work-supporting member, a table on which one of said members is mounted, fluid pressure means for actuating said table, means for procuring a movement of said table for an axial separation between said members, an ejector for procuring discharge of a workpiece from the work-supporting member, a fluid pressure motor for actuating said ejector, and means for actuating said fluid pressure motor by the exhaust fluid from the table actuating means during the axial separation.
23. In a grinding machine, a grinding member, a centerless work-supporting member, a table on which one of said members is mounted, fluid pressure means for actuating said table, means for procuring a movement of said table for an axial separation between said members, an ejector for procuring discharge of a workpiece from the work-supporting member, a fluid pressure motor for actuating said ejector, means for actuating said fluid pressure motor by the exhaust fluid from the table actuating means during the axial separation, and means operative upon reversal of the table movement for actuating the table motor by the exhaust fluid from the ejector motor.
24. In a grinding machine, a grinding member, a centerless work-supporting member, a table on which one of said members is mounted, fluid pressure means for actuating said table, means for procuring a movement of said table for an axial separation between said members, an ejector for procuring discharge of a workpiece from the work-supporting member, a fluid pressure motor for actuating said ejector, means for actuating said fluid pressure motor by the exhaust fluid from the table actuating means during the axial separation, and means operative upon reversal of the table movement for procuring return of said ejector to original position before the return of said members to operative position.
25. In a grinding machine, a grinding member and a centerless work-supporting member, a table on which one of said members is mounted, a fluid pressure motor for actuating said table, means for procuring a movement of the table for an axial separation between said members, an ejector for a workpiece in the work-supporting member and fluid pressure means connected to the table motor and actuated by the exhaust fluid from said motor for actuating the ejector.
26. In a grinding machine, a grinding member and a work-supporting member, a table on which one of said members is mounted, said table procuring a relative axial movement between said members, an ejector for removing a finished workpiece from the work-supporting member, size determining means, means under the control of said size determining means for procuring movement of the table for an axial separation between said members, fluid pressure means for withdrawing the size determining means from the workpiece, fluid pressure means for actuating the ejector while said members are separated, and means associated with said withdrawing means to provide for operation of said ejector operating means only when the size determining means are out of engagement with the workpiece.
27. In apparatus of the class described, a table having operative and an inoperative position, a fluid motor including a cylinder and piston for actuating said table, means responsive to the table movement for reversing the flow of fluid to

5 said cylinder, a second fluid motor, means operative during the movement of the table into inoperative position for directing exhaust fluid from said first motor to said second motor for actuating the latter, means operative on reversal of the table movement for directing fluid under pressure to said second motor and for directing the exhaust fluid from said second motor to the first motor for actuating the latter, and a by-pass in said second motor to provide for discharge of fluid through said motor for a continued movement of said first motor when the piston of the second motor reaches the end of its stroke.

10 28. In a grinding machine, a grinding member, a centerless work-supporting member, a table on which one of said members is mounted, fluid pressure means for actuating the table, means for procuring a movement of said table for an axial separation between said members, an ejector for 15 procuring discharge of a workpiece from the work-supporting member, a fluid pressure motor for actuating said ejector, means for actuating said fluid pressure means by the exhaust fluid from the fluid pressure motor, and a by-pass in 20 said fluid pressure motor to provide for discharge of fluid through said motor for a continued operation of said fluid pressure means when the fluid pressure motor reaches the end of its stroke.

25 29. In a grinding machine, a grinding member and a work-supporting member, fluid pressure means for procuring an axial reciprocation between said members and an elongated movement of separation between said members, an ejector for procuring discharge of a workpiece from a 30 work-supporting member, a fluid pressure motor for actuating said ejector, interconnecting means between said motor and said fluid pressure means for actuation of said ejector in response to operation of said fluid pressure means, a gage, fluid 35 pressure means for withdrawing the gage from the workpiece, and a valve in said interconnecting means to provide for the flow of fluid from the fluid pressure means to the fluid pressure motor only when the fluid pressure means for 40 withdrawing the gage is operative.

45 30. In apparatus of the class described, a work-supporting structure comprising a rotating drive wheel engageable with the periphery of a workpiece, a supporting member engaging said workpiece and a pressure member holding said workpiece against said wheel and supporting member, a plug gage adapted to enter the bore of the

5 workpiece when the latter reaches a desired size, means under the control of said gage for procuring a radial discharge of a workpiece from the work-supporting structure, means for withdrawing the gage member from within the bore of the 10 workpiece, means for actuating said discharging means, and means providing for operation of said actuating means only after the operation of said withdrawing means by which the gage is removed from the bore of the workpiece.

15 31. In a grinding machine, a grinding member, a centerless work-supporting member, a table on which one of said members is mounted, fluid pressure means for actuating the table, means for procuring a movement of said table for an axial separation between said members, an ejector for 20 procuring discharge of a workpiece from the work-supporting member, a fluid pressure motor for actuating said ejector, means for actuating said fluid pressure means by the exhaust fluid from the fluid pressure motor, a by-pass in said fluid pressure motor to provide for discharge of fluid through said motor for a continued operation of said fluid pressure means when the fluid pressure motor reaches the end of its stroke, and 25 a second by-pass in said fluid pressure motor to provide for discharge of fluid through said motor for a continued operation of said fluid pressure means when the fluid pressure motor reaches the opposite end of its stroke.

30 32. In a grinding machine, a grinding member, a centerless work-supporting member, a table on which one of said members is mounted, fluid pressure means for actuating said table, means for procuring a movement of said table for an axial 35 separation between said members, an ejector for procuring discharge of a workpiece from the work-supporting member, a fluid pressure motor for actuating said ejector, size determining means engageable with the bore of the workpiece, means 40 for withdrawing said size determining means from the bore of the workpiece, means for actuating said fluid pressure motor by the exhaust fluid from the table actuating means during the axial separation, and valve means associated with 45 said withdrawing means to provide fluid connection from the table actuating means to said fluid pressure motor, only when the gage is fully withdrawn from the bore of the workpiece.
